UNITED STATES PATENT OFFICE.

PETER KUCERA, OF CONNELLSVILLE, PENNSYLVANIA, ASSIGNOR TO CAPSTAN GLASS COMPANY, OF CONNELLSVILLE, PENNSYLVANIA, A CORPORATION OF DELAWARE.

SAFETY DEVICE FOR PRESSES.

Application filed May 15, 1920. Serial No. 381,579.

This invention relates broadly to presses and more specially to safety devices for presses.

The principal object of the present invention is a safety device to stop the normal operation of the pressing mechanism when an abnormal amount of material is accidentally retained between the pressing members.

Another object of the present invention is the provision of a safety device for preventing injury to the pressing mechanism when the material being pressed sticks or is caught by one of the pressing members whereby an abnormal amount of pressing material might be collected between the pressing members during the continuation of the machine.

A still further and important object of the present invention is a safety device for machines for pressing glass wherein the pressing operation is automatically stopped when a charge of glass sticks to one of the pressing members.

Another and important object of the present invention comprises a safety device for glass presses utilizing a plunger and wherein the press is automatically stopped when glass adheres to the plunger, and it must be manually reset for further operation.

A still further object of the present invention is the provision of a safety device for a glass press, wherein the pressing function is automatically stopped when glass adheres to the plunger and wherein the molds continue to be presented at a suitable charging station to carry away glass charges which may be presented to the press, while the press is not functioning to produce finished ware.

Other and further objects of the present invention will in part be obvious, and will in part be pointed out hereinafter and by reference to the accompanying drawings forming a part hereof and wherein like parts are represented by like characters throughout the several figures.

Realizing that the present invention may be embodied in constructions other than those specifically shown and described, it is to be understood that the description and

drawings disclose one form of the present invention and that this disclosure is to be considered as illustrative and not to be taken in the limiting sense.

Figure 1 is a more or less diagrammatical view illustrating a complete organization comprising one form of the present invention;

Figure 2 is a detail sectional view of a portion of the safety operating device with the "feeler" finger withdrawn;

Figure 3 is a figure similar to Figure 2 showing the "feeler" finger being operated due to a charge of glass adhering to the plunger;

Figure 4 is a sectional detail plan view illustrating the mounting for the safety operating finger mechanism whereby the same may be adjusted as may be required.

In the operation of pressing mechanism, particularly glass presses, it sometimes happens that the material pressed will adhere to one of the molding or pressing members. Where the press is automatically fed, as glass presses usually are, the sticking of a charge to one of the pressing members causes a large overcharge to be presented for the succeeding pressing operation. This overcharge may cause the press to be badly strained or even broken and unless the press is immediately stopped the accumulation continues until serious injury to the mechanism is almost certain to result. In pressing glassware it is necessary that the finish on the pressing or molding parts must be maintained, otherwise the ware produced will be of inferior quality. When glass sticks to the molding parts it quickly hardens and the next pressing operation crushes the hardened glass and scratches or injures the molding elements so that it is necessary to replace these parts to continue the operation of the machine to make high quality ware.

Glass presses, as above stated, are commonly automatically fed and in the manufacture of glass by the use of automatic feeders and automatic presses there are a number of constant conditions which must be maintained in order to satisfactorily produce ware, and if these conditions are disturbed it entails a great loss of time

to bring the conditions back to normal. One of the most critical elements in the production of glass by automatic machinery is the element relating to feeding the glass from the furnace to the press. If a feed is stopped the glass tends to freeze and it may require a serious loss of time in order to have the glass running again after it has been stopped. If the glass runs too rapidly from the furnace it becomes too limp for the pressing operation and must be cooled before production can be resumed. In view of these facts it is desirable that the glass feed continue normally even though the press may be disabled temporarily. Where glass sticks to the plunger of the press it is necessary that this glass be removed before the next pressing operation. At the same time, as above stated, it is desirable to have the feed mechanism continue to deliver glass. In order to attain this result the present invention provides for merely stopping the operation at the pressing station of the press, but does not interfere with the step by step rotation of the press whereby molds are successively presented to the charging station beneath the feeder. When the pressing is stopped in order to clear the glass which has adhered to the pressing mechanism the press operator merely removes the charges from the molds as they pass and as soon as he has cleared away the adhered charge from the plunger, or mold, the press is thrown back into normal operation and operation is immediately resumed. The present invention also provides that when glass does adhere, the pressing device is automatically cut out and the pressing operation cannot be resumed without manual resetting of the parts.

One embodiment of the present invention may comprise a commercial type of glass press having a step by step rotated table carrying relatively movable pressing members, comprising a plunger and a series of suitable matrix molds. The relative movement between these parts is usually accomplished by compressed air and the parts are usually controlled by a timing mechanism. The present invention contemplates connecting the timing mechanism with a suitable "feeler" finger so that this finger moves forward between each pressing operation to determine if the pressing members are clear. The finger is moved very closely to, but without contact with the pressing mechanism, preferably the plunger near its lower end, and if the plunger is clear the pressing operation continues. If any glass adheres to the plunger the finger, in striking the glass, automatically operates to cut off the power from the pressing station so that the pressing will not be resumed until the mechanism is manually reset, thereby preventing any breakage due to pressing when

glass is adhering to the parts of the forming devices.

Referring now to the drawings and more particularly to Figure 1, a commercial press 1 is provided with the usual plunger stem 2 which carries the plunger head 4 which is adapted to cooperate with the matrix mold 5. This mold also cooperates with the usual ring mold 6 and the operating mechanism therefor. The matrix mold 5 in the present illustration is one of a series which is carried by a rotatable mold table 7 and is adapted to be lifted by the piston rod 8 of the pressing cylinder 9 to mold a suitable charge of glass between the walls of the matrix mold 5 and the plunger head 4 when the molds are properly positioned at the pressing station. The pressing cylinder 9 is operated in the usual manner by compressed air fed through the pipes 10 and 11 and controlled by a suitable timing mechanism 12 such as is common in the art. This timing mechanism is fed by a main air line 14 and controls the operations of the press. The "feeler" finger mechanism comprises a cylinder 15 which is mounted upon the press uprights 16 and 17 and is connected with the timer 12 by means of the pipes 18 and 19. This cylinder (Figs. 2 and 3) is provided with a piston 20 which is connected with the hollow piston rod 21, in which is mounted "feeler" finger 22 which comprises the stem for an air valve 24. The hollow piston rod 21 extends through a cylindrical neck 25 which may be carried by the cylinder head 26 and the hollow piston rod 21 is slotted as at 27. From Figure 3 it will be noted that the slots 27 lie within cylindrical neck 25 when the piston 20 is in its forward position and if any glass 28 is adhering to the plunger head 4 it will be noted that the valve 24 is opened, thereby permitting the air back of the piston 20 to escape into the cylindrical neck 25 and since this neck is connected by a pipe 29 with an air cylinder 30 the compressed air back of the piston is immediately admitted to the cylinder 30. This cylinder 30 carries a suitable piston 31 which is connected with the piston rod 32 that is adapted to engage the operating lever 34 of the cut-off valve 35 in the main line 11 to the pressing cylinder so that when the compressed air enters the air cylinder 30 the piston 31 and piston rod 32 move forward to actuate the lever 34, whereby the operating air to the main cylinder is cut off. The air cylinder 30 is provided with a vent valve 36 so that the air in the cylinder may escape to permit the parts to be reset after the device has once functioned. The lever 34 is not attached to the piston rod 32, and therefore it is necessary to manually reset the lever to open the cut-off valve 35. This is an added advantage because the resetting is therefore deliberate on the part of the operator.

Referring now to Figure 4, which is a plan view of the "feeler" finger operating mechanism, it will be noted that the cylinder 15 is mounted upon the cross arm 37 by stub bolts 38 which cooperate with slots 39 in the flanges 40 on the cylinder. This mounting permits adjustment of the device to and from the axis of the plunger head 4 in order to accommodate for different size plungers 10 which may be used. The cross arm 37 is mounted upon the press uprights 16 and 17 by suitable clamp sleeves 41 to permit a vertical adjustment of the "feeler" finger in order that this finger may cooperate with the 15 lower portion of the plunger head 4 and be adjustable for different lengths of plunger heads. It will be understood that the pipe connections to these adjustable parts are flexible, as is common in the art where flexibility is required.

In the operation of the present device it will be noted that the timing mechanism is so arranged that the "feeler" finger goes forward just prior to the pressing operation.

25 While the plunger 4 is clear the press continues to function normally. If any glass sticks to the plunger (as shown in Fig. 3) the "feeler" finger contacts with this glass, thereby opening the air line which leads to 30 the control air-cylinder 30 and which cylinder closes the main air line 11 to the pressing cylinder; consequently the pressing mechanism is disabled, and while the press table will continue to rotate in the step by 35 step motion, the charges being fed to the molds will remain unpressed, and the operator removes the unpressed charges from the molds until the press is cleared. After the chilled glass has been removed from the 40 plunger the operator reopens the cut-off valve 35 and normal operation of the press is resumed. It will be noted that the present mechanism in no way disturbs the function of the feed mechanism or of the parts, 45 other than the pressing operation.

Having thus described my invention, what I claim is:

1. In a glass machine and the like, the combination of a matrix mold, a plunger adaptable to enter said matrix mold, means for causing a relative movement between said plunger and said matrix mold, a detector cylinder mounted adjacent said plunger with the axis of said cylinder substantially at right angles to the axis of said plunger, a piston within said cylinder, a hollow slotted piston rod connected to said piston and extending toward said plunger, a feeler finger within said hollow piston rod, a valve connected with said feeler finger and adapted to be lifted to permit pressure back of said piston to escape through slots in said hollow piston rod, a timing mechanism controlling said means and being operatively connected to said cylinder, and devices operatively

connected with said valve to render said means inoperative when said valve is raised.

2. In a glass machine and the like, the combination of a matrix mold, a rotatable table carrying said mold, a plunger adaptable to enter said matrix mold, means for causing a relative movement between said plunger and said matrix mold, a detector cylinder mounted adjacent said plunger with the axis of said cylinder substantially at right angles to the axis of said plunger, a piston within said cylinder, a hollow slotted piston rod connected to said piston and extending toward said plunger, a feeler finger within said hollow piston rod, a valve connected with said feeler finger and adapted to be lifted to permit pressure back of said piston to escape through slots in said hollow piston rod, a timing mechanism controlling said means and being operatively connected to said cylinder, and devices operatively connected with said valve to render said means inoperative when said valve is raised, and without stopping said table.

3. In a glass machine and the like, the combination of a matrix mold, a plunger adaptable to enter said matrix mold, means comprising a pneumatic ram for causing a relative movement between said plunger and said matrix mold, a detector cylinder mounted adjacent said plunger with the axis of said cylinder substantially at right angles to the axis of said plunger, a piston within said cylinder, a hollow slotted piston rod connected to said piston and extending toward said plunger, a feeler finger within said hollow piston rod, a valve connected with said feeler finger and adapted to be lifted to permit pressure back of said piston to escape through slots in said hollow piston rod, a timing mechanism controlling said means and being operatively connected to said cylinder to admit air to said cylinder prior to the operation of said ram, and devices operatively connected with said valve to render said means inoperative when said valve is raised.

4. In a glass machine and the like, the combination of a matrix mold, a plunger adaptable to enter said matrix mold, means for causing a relative movement between said plunger and said matrix mold, a detector cylinder mounted adjacent said plunger with the axis of said cylinder substantially at right angles to the axis of said plunger, means to adjust said cylinder relatively to said plunger, a piston within said cylinder, a hollow slotted piston rod connected to said piston and extending toward said plunger, a feeler finger within said hollow piston rod, a valve connected with said feeler finger and adapted to be lifted to permit pressure back of said piston to escape through slots in said hollow piston rod, a timing mechanism controlling said means and being operatively connected to said cylinder, and devices operatively

trolling said means and being operatively connected to said cylinder, and devices operatively connected with said valve to render said means inoperative when said valve is raised.

5. In a glass machine and the like, the combination of a matrix mold, a rotatable table carrying said mold, a plunger adaptable to enter said matrix mold, means comprising a pneumatic ram for causing a relative movement between said plunger and said matrix mold, a detector cylinder mounted adjacent said plunger with the axis of said cylinder substantially at right angles to the axis of said plunger, a piston within said cylinder, a hollow slotted piston rod connected to said piston and extending toward said plunger, a feeler finger within said hollow piston rod, a valve connected with said feeler finger and adapted to be lifted to permit pressure back of said piston to escape through slots in said hollow piston rod, a timing mechanism controlling said means and being operatively connected to said cylinder, and devices operatively connected with said valve to render said means inoperative when said valve is raised and without stopping said table.

6. In a glass machine and the like, the combination of a matrix mold, a rotatable table, a plunger adaptable to enter said matrix mold, means comprising a pneumatic ram for causing a relative movement between said plunger and said matrix mold, a detector cylinder mounted adjacent said plunger with the axis of said cylinder substantially at right angles to the axis of said plunger, means to adjust said cylinder relatively to said plunger, a piston within said cylinder, a hollow slotted piston rod connected to said piston and extending toward said plunger, a feeler finger within said hollow piston rod, a valve connected with said feeler finger and adapted to be lifted to permit pressure back of said piston to escape through slots in said hollow piston rod, a timing mechanism controlling said means and being operatively connected to said cylinder to admit air to said cylinder prior to the operation of said ram, and devices operatively connected with said valve to render said means inoperative when said valve is raised, and without stopping said table.

7. In a glass machine and the like, the combination of a matrix mold, an intermittently rotatable table upon which said mold is mounted, a plunger adaptable to enter said matrix mold, means for causing a relative movement between said plunger and said matrix mold, a detector comprising a feeler finger adapted to be moved toward and adjacent to said plunger; a piston for actuating said finger, a valve connected with said feeler finger and adapted to be lifted when said finger strikes an obstruction to permit

pressure back of said piston to pass under said valve, a timing mechanism controlling said means and being adapted to operate said piston, and devices operatively connected with said valve to render said means inoperative when said valve is raised.

8. In a pressing mechanism or the like, forming members, a rotatable table carrying certain of said members, means to operate the forming members to mold plastic material between said forming members, and a detecting device operable to render said means inoperative when the molded material sticks to a certain one of the forming members, without stopping the rotation of said table.

9. In a pressing mechanism or the like, forming members, a rotatable table carrying certain of said members, means comprising a pneumatic ram to operate the forming members to mold plastic material between said forming members, and a detecting device actuated between molding operations and operable to render said ram inoperative when the molded material sticks to a certain one of the forming members, without stopping the rotation of said table.

10. In a glass pressing mechanism, a matrix mold, a plunger adapted to enter said matrix mold, means for causing a relative movement between said plunger and said mold to press glass in the said mold, in combination with a detector mechanism comprising a cylinder mounted adjacent said plunger, a piston within said cylinder, a valve in the head of said piston, a feeler finger connected with said valve, devices to operate said feeler finger in such manner that said feeler finger will contact with any material between the limit of travel of the end of said feeler finger and said plunger, and mechanism operated by said valve to render said means inoperative when said feeler finger meets an obstruction.

11. In a glass pressing mechanism, a matrix mold, a plunger adapted to enter said matrix mold, means for causing a relative movement between said plunger and said mold to press glass in the said mold, in combination with a detector mechanism comprising a cylinder mounted adjacent said plunger, devices to adjust said cylinder vertically, a piston within said cylinder, a valve in the head of said piston, a feeler finger connected with said valve, devices to operate said feeler finger in such manner that said feeler finger will contact with any material between the limit of travel of the end of said feeler finger and said plunger, and mechanism operated by said valve to render said means inoperative when said feeler finger meets an obstruction.

12. In a glass pressing mechanism, a matrix mold, a plunger adapted to enter said matrix mold, means for causing a relative

- movement between said plunger and said mold to press glass in the said mold, in combination with a detector mechanism comprising a cylinder mounted adjacent said plunger, a piston within said cylinder, a valve in the head of said piston, devices to adjust said cylinder horizontally, a feeler finger connected with said valve, devices to operate said feeler finger in such manner that said 5
feeler finger will contact with any material between the limit of travel of the end of said feeler finger and said plunger, and mechanism operated by said valve to render said means inoperative when said feeler finger 10
meets an obstruction.
18. In a glass pressing mechanism, a matrix mold, a plunger adapted to enter said matrix mold, means for causing a relative movement between said plunger and said 15
mold to press glass in the said mold, in combination with a detector mechanism comprising a cylinder mounted adjacent said plunger, devices to adjust said cylinder vertically, a piston within said cylinder, a valve in the 20
head of said piston, means to adjust said cylinder horizontally, a feeler finger connected with said valve, devices to operate said feeler finger, in such manner that said feeler finger will contact with any material between the 25
limit of travel of the end of said feeler finger and said plunger, and mechanism operated by said valve to render said means inoperative when said feeler finger meets an obstruction.
- 30
35
40
14. In a pressing mechanism, forming members, operating means to cause a relative movement between said forming members to mold plastic material between said members in combination with a detecting device movable to a position adjacent one of said forming members after each pressing operation,

and mechanism controlled by said detecting device to render the said operating means inoperative when material sticks to a certain forming member in the path of said detecting device. 45

15. In a pressing mechanism, forming members, operating means to cause a relative movement between said forming members to mold plastic material between said 50
members, in combination with a detecting device movable to a position adjacent one of said forming members after each pressing operation, means for adjusting said device relatively to certain of said forming members, and mechanism controlled by said detecting device to render the said operating means inoperative when material sticks to a certain forming member in the path of said 55
detecting device. 60

16. In a glass press and the like, the combination of a matrix mold and plunger adapted to enter said matrix mold, means for causing a relative movement between said plunger and said mold for pressing glass between the plunger and mold, a feeler finger adapted to be projected into proximity of the plunger during the interval between pressing operations, a valve normally closed and adapted to be opened by said 65
feeler finger when there is any substance of predetermined thickness between the limit of travel of the finger and said plunger, a cylinder provided with a piston operatively connected with said valve in such manner 70
that when said valve is open fluid is admitted to said cylinder to move said piston, and disabling mechanism for said means being operated by said piston to render said means inoperative when said valve is open. 75

PETER KUCERA.
